UNITED STATES PATENT OFFICE.

ALBERT H. BRYANT AND EDWARD G. TUCK, OF PORTLAND, OREGON.

RAFT FOR TRANSPORTING TIMBER.

Application filed July 6, 1927. Serial No. 203,800.

The object of our invention is to provide a raft, which is adapted to restrain the movement of the logs or timbers composing the raft, longitudinally, vertically or transversely of the raft, and relatively to each other. Experience has demonstrated that where the logs composing the raft are permitted such movement they are prone to set up such leverage as to cause the breaking of the lashings, and thus permit the raft to go to pieces; and that such as likely to occur even in only moderately rough water.

We attain our object by providing in the first place a rectangular frame composed of rigid, preferably one-piece parallel spaced buoyant side-members, extending from end to end of the frame, and tied together at their ends by end-members or spreaders.

Within such frame the logs are then supported and secured by suitable cables, fastened to the sides of the frame and extending around the bottom and top of the logs comprising the raft. By this construction, the angular movement of the logs relatively to each other in the longitudinal, vertical or transverse planes of the raft is effectively prevented, and no leverage is set up tending to break the cables.

A further feature of our invention is to build a raft capable of floating and being moved in shallow water, as over a bar. This result we attain by using for the sides of the raft frame-members having greater buoyancy than the logs composing the raft, and thereby to add to and increase the buoyancy of the raft as a whole.

To this end, we employ for the sides of the frame hollow metal, or other buoyant members of such length as to extend from end to end of the raft, and of sufficient cross section to be capable of exerting a potent buoyancy effect upon the raft.

Other features of our raft as well as the details of construction thereof are hereinafter fully described with reference to the accompanying drawings, in which:

Fig. 1 shows a plan of our raft without its load, the cables secured to the side members of the raft frame for supporting a load being shown;

Fig. 2 is a plan view of our raft loaded with logs; and

Fig. 3 is a larger scaled diagrammatic cross section of our raft, showing the same as carrying a load of logs and illustrating by the position of the raft relatively to surface

of the water the buoyancy which the frame of our raft adds to the raft as a whole; and Figs. 4 and 5 are details of a simple mode for constructing our raft frame.

As shown in the drawings, our raft consists of a frame composed of side members *a*, *a'* extending the full length of the frame and made of some material possessing greater buoyancy than the logs with which the raft is loaded. Preferably, we use one piece metal pontoons for the sides of our raft; that is to say, the pontoons being of such length as to extend from end to end of the raft frame.

The ends of the side members of our frame are connected by suitable spreaders *b*, *b*. These may consist of logs *b'* on the ends of which are secured caps *c* provided with an eye *d* adapted to be placed on the ends *a'* of the side members, *a*, *a'*, and secured against slipping off as by a key *e* as illustrated by Fig. 4. To the side members *a*, *a'* is secured a netting as *f*, the netting being made of cables and arranged to support the logs which shall constitute the load of the raft.

The load of logs *g* is secured in place on the netting *f* by cables *h* as more clearly shown by Fig. 3.

In order to provide a strong tie for the load supporting netting *f* and the cables *h*, we encircle the side members or pontoons *a*, *a'* with bands *i*, preferably using railroad rails for that purpose and to such bands secure clevises *j* to which the cables of the load-supporting netting *f* or the load-securing cables *h* are fastened. To prevent the chafing of the cables composing the load-supporting netting the latter is preferably made of diverging short cable lengths *h'* tied together by a ring *k* as illustrated by Fig. 5.

As previously mentioned, the side-members are constructed to supplement, and increase materially, the buoyancy of the load of the logs, so that the load may be floated in shallow water; and to this end the load-supporting netting *f* is arranged relatively to the spreaders *b* of the raft-frame so as to support the bottom of the load substantially on the plane of the bottom of the side members *a*, *a'* of the raft frame.

We claim:

1. A raft of the character described comprising a substantially rectangular frame composed of rigid side-members extending the full length of the frame and rigid bands secured on the side-members, fastening elements secured to said bands, load carrying

members comprising diverging cable-lengths secured to said fastening elements of the side-members and connected intermediate the latter, load securing cables also fastened to said fastening elements.

2. A raft of the character described comprising a substantially rectangular frame composed of rigid pontoon-like side-members extending the full length of the frame and 10 rigid bands secured on the side-members, spreaders connecting the ends of said side members, fastening elements secured to said bands, load carrying members, load securing cables also fastened to said fastening elements, the load carrying cables being arranged relatively to the said spreaders of the raft-frame, so as to support the bottom of the load approximately in the plane of the bottom of the side members of the raft-frame.

3. A raft of the character described comprising a substantially rectangular frame composed of rigid pontoon-like side-members extending the full length of the frame, rigid bands secured on the side-members, spreaders connecting the ends of said side members, fastening elements secured to said bands, load carrying members comprising diverging cable-lengths secured to said fastening elements of the side-members and connected intermediate the latter load securing cables also fastened to said fastening elements, the load carrying cables being arranged relatively to the said spreaders of the raft-frame, so as to support the bottom of the load approximately in the plane of the bottom of the side members of the raft-frame.

ALBERT H. BRYANT.
EDWARD G. TUCK.
